CHEST OF DRAWERS OR THE LIKE

Joseph E. Adkinson, 3807 Leland St.,
Chevy Chase, Md. 20015

Filed Apr. 17, 1970, Ser. No. 22,482

Term of patent 7 years

Int. Cl. D6—04

U.S. Cl. D33—6

FIG. 1

FIG. 1 is a perspective view of the chest of drawers.
FIG. 2 is a view in side elevation of the chest of drawers of FIG. 1.

The side of the article not shown is a mirror image of the side shown while the back is plain and unornamented.

I claim:

The ornamental design for a chest of drawers or the like, substantially as shown and described.
